UNITED STATES PATENT OFFICE.

ALFRED J. JOHNSON, OF GRAND RAPIDS, MICHIGAN, ASSIGNOR TO J. W. YORK AND SONS, OF GRAND RAPIDS, MICHIGAN, A CORPORATION OF MICHIGAN.

DESIGN FOR A CORNET.

45,091.

Specification for Design.

Patented Dec. 30, 1913.

Application filed May 5, 1913. Serial No. 765,690. Term of patent 14 years.

To all whom it may concern:

Be it known that I, ALFRED J. JOHNSON, a citizen of the United States, residing at Grand Rapids, in the county of Kent and State of Michigan, have invented a new, original, and ornamental Design for a Cornet, of which the following is a specification, reference being had to the accompanying drawing, forming part thereof, in which—

Figure 1 is a front elevation of a cornet

embodying my invention; Fig. 2 is an inverted plan view of the same; and Fig. 3 is a rear elevation of the same.

I claim:—

The ornamental design for a cornet, as shown.

ALFRED J. JOHNSON.

Witnesses:

PALMER A. JONES,
HAROLD O. VAN ANTWERP.
